ABSTRACT

A receiving device comprising a filtering section consisting of as many band-pass analysis filters as there are different component frequencies in the signals which can be received, and a processing section enabling an analysis of the energy in the individual filters.

DIGITAL FILTERING FOR DETECTING COMPONENT FREQUENCIES FROM A SET OF PREDETERMINED FREQUENCIES

The present invention concerns a numerical frequency receiver, for use more particularly in the telecommunications industry.

For some years now, use has been made in telephone installations of the multifrequency code, whereby signalling between telephone exchanges may be obtained by means of voice frequency currents; a similar type of signalling will probably be used in future between the subscriber and his connecting exchange for routing the number signals transmitted by keyboard.

The apparatus, which has to ensure correct reception of information thus transmitted, despite the presence of numerous parasitic signals due to the poor quality of the lines, is the frequency receiver, which is connected via the connection network either to the circuit or to the subscriber's line.

Since the use of a single transmission frequency presents certain risks of confusion with parasitic sources, the multifrequency code provides, for the circuits, the transmission of two frequencies out of five, while the keyboard code utilized for subscribers' lines, transmits on two groups of frequencies, of which it is necessary to receive one frequency of each group.

As prior art, frequency receiving devices are known which receive analogue signals, switched then filtered by conventional means, such as inductances and capacitors, but owing to the variations in the characteristics of the constituent elements, these devices do not show good stability in the course of time.

The frequency receiving device according to the invention does not receive analogue signals but numerical signals in the form of binary coded pulses. Each circuit, which is the seat of voice audio frequency signaling, is connected to a coder on entering the exchange; the voice frequencies are sampled there at the frequency of 8000 c/s, for example, and the measurement of the sampled amplitudes is transmitted to the frequency receiver every 125 μ s by a binary number of 10 bits, which corresponds to the possible appreciation of about 1,000 different levels of the amplitude to be measured.

The device according to the invention is based on the theory of numerical linear filters, which are defined by finite difference equations, the solution of which is effected by means of Z transformation.

It is possible to quote on this subject an article by C.M. RADER and B. GOLD entitled: "DIGITAL FILTER DESIGN TECHNIQUES IN THE FREQUENCY DOMAIN" published in the American periodical PROCEEDING OF THE I.E.E.E. of February, 1967; an article by H.A. HELM entitled "THE Z TRANSFORMATION" published in the American periodical "BELL SYSTEM TECHNICAL JOURNAL" of January, 1959 and an article published in "L'ONDE ELECTRIQUE" of February, 1965 entitled "LA TRANSFORMATION Z ET LES EQUATIONS AUX DIFFÉRENCES (THE Z TRANSFORMATION AND DIFFERENCE EQUATIONS)" by R. LEGROS.

The state of the theory having thus been recapitulated, an explanation will be given in the description with a view to the application of the said theory to the device according to the invention.

The numerical frequency receiving device according to the invention is more particularly characterized in that it consists of a "filtering" part and a "treatment" part; the filtering part comprises as many pass-band analysis filters as there are different component frequencies in the signals capable of being received; the treatment parts permits an analysis of the energy in the different filters.

According to one feature of the invention, each analysis filter comprises a computing circuit and a store; the operations to be performed by the computing circuit are:

$$Y = X - B_2 Y_2 - B_1 Y_1$$

$$S = Y - Y_2$$

where

X is the input sample, arriving at the sampling frequency,

S is the output sample, leaving at the same sampling frequency,

B_1 and B_2 are constant coefficients characterizing the filter,

Y_1 and Y_2 are intermediate results, the store of the filter retaining the quantities B_1 , B_2 , Y_1 and Y_2 .

According to another feature of the invention, the quantities B_1 and B_2 , Y_1 and Y_2 are stored in the form of logarithms to the base 2, such that multiplications are replaced by additions of logarithms, and divisions by subtractions of logarithms, while normal additions and subtractions are performed on linear quantities requiring the provision of a converter of logarithmic quantities into linear quantities and of the reverse converter of linear quantities into logarithmic quantities.

According to yet another feature of the invention corresponding to the treatment circuit are a summation circuit for the absolute values of the output signals, a store containing the "sum" results of each filter of the receiver for a certain number of samples and a circuit for the analysis of the energy in the different filters of the receiver.

According to yet another feature of the invention, the device being controlled by a time base, the operation of an analysis filter having one cell is performed in four elementary times; in the time t_1 , the product $B_2 Y_2$ is formed and is registered in the register 1, while the new sample X is registered in the register 2; in the time t_2 , the operations $X - B_2 Y_2$ and $B_1 Y_1$ are performed, the first result being recorded in the register 2 and the second result in the register 1; in the time t_3 , the operation $Y = X - B_2 Y_2 - B_1 Y_1$ is performed, the result of which is recorded in register 2; in the time t_4 , the operation $S = Y - Y_2$ is performed, the result of which is recorded in the register 3.

According to yet another feature of the invention, the store of the sums of the samples is a circulation store advancing in synchronism with the instants of computation relative to each of the filters comprising a word of 12 bits per filter.

According to yet another feature of the invention, the circuits analyzing the energy in the filters are formed by four shift registers receiving on command in parallel and at the same instant the contents of the first four words starting from the output of the shift store of the sums of the samples; after posting and shifting of

these registers, heavily weighted in front, the outputs of the four shift registers enter the maximum value test circuit, the filter having the maximum energy corresponding to the register having the first 1 at its output.

One advantage of the device according to the invention is its stability, the characteristics of the numerical filters, being connected solely to precisions of arithmetical computations, are sensitive only to the operational defects of the logical circuits constituting them; that is to say, they do not present any shunts, but only open faults in the case of failure of a logical circuit.

Another advantage of the device according to the invention is that the characteristics of the filters being fixed by the coefficients B_1 and B_2 , all that is necessary for changing the characteristics (pass band, attenuation) of a filter, is to modify the coefficients, which may be done simply by modifying the matrix of the store of the coefficients.

Furthermore, the invention will be well understood and other features and advantages will appear from the detailed description, which will be given with reference to the figure of the accompanying drawings.

FIG. 1 gives a descriptive representation of the finite difference equation.

FIG. 2 gives a descriptive representation of the finite difference equation in "series" combination of two equations having differences of 1st or 2nd order.

FIG. 3 gives a symbolic representation of a type of filter selected for the frequency receiver according to the invention.

FIG. 4 shows a general diagram of a frequency receiver according to the invention.

FIG. 5 gives a detailed diagram of a computing circuit according to the invention.

FIG. 6 gives a detailed diagram of the "treatment" part of the device according to the invention.

FIG. 7 offers a comparison of the output signals of two filters receiving the same input signal.

FIG. 8 gives a coded example of the operation of a two-cell filter on a first input sample.

FIG. 9 gives a coded example of the operation of the same two-cell filter on a second input sample.

To relieve the reader of the necessity of referring to other documents, a summary of the theory of numerical filters is given in the following.

It is known that linear continuous filters are defined by a linear differential equation, that is to say, if the excitation of the filter is $e(t)$ and the response $r(t)$, the relation between $e(t)$ and $r(t)$ is given in the form of a linear differential equation (the variable t is the time). When the Laplace transform is used, s , complex frequency, is the variable; the excitation transform is $E(s)$, the response transform is $R(s)$. The relation between $E(s)$ and $R(s)$ is algebraic and is written:

$$R(s) = E(s) \times H(s)$$

$H(s)$ is called the transfer function of the filter or again the function of the system.

The problem of the definition of continuous filters is to determine the function $H(s)$ which gives the desired response to a known excitation and which may be realized physically.

If the theory of continuous linear filters is based on the theory of linear differential equations, the theory of numerical linear filters is based on the theory of finite difference equations. And, just as the LAPLACE transformation is used for solving linear differential equations, the Z transformation is used for solving finite difference equations describing the numerical linear filters.

A linear, finite difference equation of order m may be written:

$$y(nT) = \sum_{i=0}^r L_i x(nT - iT) - \sum_{i=1}^m K_i y(nT - iT) \quad (1)$$

This form (1) indicates the iterative nature of the difference equation; given the m preceding values of the output y and the $(r+1)$ last values of the input x , the new value of the output y is calculated by means of the relationship (1). From the physical point of view, the input quantities x are samples of the continuous signal, and the numerical filtering in real time consists in effecting the iteration (1) each time a new sample appears, that is to say, at each sampling period T .

The definition of a numerical filter consists in determining the constants K_i and L_i which satisfy the required filtering conditions.

FIG. 1 gives a descriptive representation of the relationship (1). The closed contour

$$\sum$$

is the algebraic sum of the sum

$$\sum_{i=0}^r L_i x(nT - iT)$$

represented by the top part of the figure and of the sum

$$\sum_{i=t}^m K_i y(nT - iT)$$

represented by the bottom part of the figure. The elements multiplied by L_i and K_i are represented by triangles giving the elementary results at each sampling period, the sum of which forms the closed contour.

In practice, instead of equations of order m , "series," "parallel" and "series-parallel" combinations of 1st or 2nd order difference equations are used. For example, the two equations:

$$\begin{cases} y_1(nT) = K_{11} y_1(nT - T) + K_{12} y_1(nT - 2T) + L_{11} x(nT) \\ y_2(nT) = K_{21} y_2(nT - T) + K_{22} y_2(nT - 2T) + L_{21} y_1(nT) \end{cases} \quad (2)$$

constitute a "series" combination, in which the output y_1 of the first equation is used as input of the second equation, as shown in FIG. 2. In this figure, the triangles are always multiplying elements, and the circular contours adding elements.

The equations (2) may be written in the form of a single equation having finite differences of order 4, but the fundamental properties of the numerical filters are easier to understand on structures of the type of FIG. 2.

To pass to the Z transformation, it is assumed that the input samples $x(nT)$ and output samples $y(nT)$ are zero for $n < 0$. The Z transformation of the sequence of $x(nT)A$ is WRITTEN:

$$X(z) = \sum_{n=0}^{\infty} x(nT)z^{-n} \quad (3)$$

In practice, for certain series, there is a condensed equivalent expression of the infinite series. For example, the Z transformation of the series of $x(nT)$ such that $x(nT) = 0$ for $n < 0$ and $x(nT) = 1$ for $n \geq 0$ is:

$$X(z) = \sum_{n=0}^{\infty} z^{-n} = \frac{1}{1-z^{-1}}$$

The transformation variable z is complex and $X(z)$ is a function of this complex variable.

The Z transformation of a convergent series defines this series perfectly. By multiplying the two terms of (3) by z^{n-1} and integrating over a closed contour (C) containing the origin and the singular points (poles) of $X(z)$ we obtain (theorem of remainders):

$$x(nT) = \frac{1}{2\pi j} \int (C) X(z) z^{n-1} dz \text{ with } j = \sqrt{-1} \quad (4)$$

The inverse Z transformation therefore defines explicitly the series $x(nT)$ associated with a function $X(z)$. For certain series, the closed integration contour may be the circle of radius 1 and center 0.

We shall now use the Z transformation for obtaining an explicit solution of the linear difference equation (1) of order m . We first of all write the relationship (1) in the new form:

$$\sum_{i=0}^m K_i y(nT - iT) = \sum_{i=0}^r L_i x(nT - iT) \quad (5)$$

Taking the Z transformation of (5), we have:

$$\sum_{i=0}^m K_i \sum_{n=0}^{\infty} y(nT - iT) z^{-n} = \sum_{i=0}^r L_i \sum_{n=0}^{\infty} x(nT - iT) z^{-n} \quad (6)$$

Noting that the Z transformation of a delayed series of i samples is equal to the Z transformation of the initial series multiplied by z^{-i} , the relationship (6) becomes:

$$\left\{ \begin{array}{l} Y(z) \sum_{i=0}^m K_i z^{-i} = X(z) \sum_{i=0}^r L_i z^{-i} \\ Y(z) = X(z) \frac{\sum_{i=0}^r L_i z^{-i}}{\sum_{i=0}^m K_i z^{-i}} = X(z) \cdot H(z) \end{array} \right. \quad (7)$$

Thus, the Z transformation of the output y is given as the product of the Z transformation of the input x and the function $H(z)$, characteristic of the system and analogous to a transfer function; $H(z)$ is a rational fraction in z^{-1} and is a function of the constant coefficients of the finite difference equation. Taking the inverse Z transformation of $Y(z)$, $y(nT)$ is defined by a relationship of type (4).

If we take as input signal

$$x(nT) = 1 \text{ for } n=0$$

$$x(nT) = 0 \text{ for } n \neq 0$$

that is to say, what may be called unit stage, then, in (7), $X(z) = 1$ and $Y(z) = H(z)$, and taking the inverse Z transformation, it will be seen that the inverse transformation of $H(z)$ is the response of the system to the signal $x(nT)$ defined earlier, that is to say, as it were, at unit stage.

It may be seen now how the function $H(z)$ permits characterization of the frequency selectivity of the system it defines. Assuming that the input signal is the complex signal:

$$x(nT) = e^{jn\omega T} \quad (8)$$

The solution of equation (5), that is to say the output signal, may be written in the form:

$$y(nT) = F(e^{j\omega T}) e^{jn\omega T} \quad (9)$$

Substituting (8) and (9) in (5) gives:

$$F(e^{j\omega T}) = \frac{\sum_{i=0}^r L_i e^{-ji\omega T}}{\sum_{i=0}^m K_i e^{-ji\omega T}} = H(e^{j\omega T})$$

The response to a sampled sinusoidal input signal may readily be derived from this expression.

It is now possible to examine the definition techniques of numerical filters, one known as pulse invariance technique and the other as frequency sampling technique, the former being best adapted to the definition of the resonators and the latter to the definition of banks of pass-band filters.

a. Pulse invariance technique.

It is accepted that a numerical filter having a pulse response equal to the sampled pulse response of a given continuous filter may be defined starting from the following agreement:

$$Y(s) = \sum_{i=1}^m \frac{Ai}{s+si} = \sum_{i=1}^m \frac{Ai}{1-e^{-\alpha T} z^{-1}} = H(z)$$

45

Thus, most resonant circuits have, as transfer function, one of the two following forms:

$$\frac{s+a}{(s+a)^2+b^2} \text{ and } \frac{b}{(s+a)^2+b^2}$$

leading to the following agreements:

$$\frac{s+a}{(s+a)^2+b^2} \Rightarrow \frac{1-e^{-\alpha T} \cdot \cos(bT) \cdot z^{-1}}{1-2e^{-\alpha T} \cdot \cos(bT) \cdot z^{-1} + e^{-2\alpha T} \cdot z^{-2}}$$

$$\frac{b}{(s+a)^2+b^2} \Rightarrow \frac{e^{-\alpha T} \cdot \sin(bT) z^{-1}}{1-2e^{-\alpha T} \cdot \cos(bT) \cdot z^{-1} + e^{-2\alpha T} z^{-2}}$$

b. Frequency sampling technique. The difference equation

$$y(nT) = x(nT) - x(nT - mT) \quad (10)$$

has as transfer function in z

$$H(z) = 1 - z^{-m}$$

which has m zeros regularly spaced on unit circle at the points:

$$z_k = e^{j2\pi k/m} \quad k = 0, 1, \dots, m-1$$

If, in relationship (10), the subtraction is replaced by an addition, the transfer function becomes $1 + z^{-m}$ which has m zeros regularly spaced in the unit circle at the points:

$$z_k = e^{j2\pi(K+1/2)/m} \quad k = 0, 1, \dots, m-1$$

The amplitude response curves of these filters, as a function of frequency, have a period of $2/m$ radians, and these filters are generally given the name of comb filters; they are sometimes used in the production of special types of filters, as will be shown later. For example, a simple resonator is connected in series with a comb filter; for the resonator, poles for $z = re^{-j\omega_0 T}$ and having no zero are taken; its transfer function in z is:

$$H(z) = \frac{1}{1 - 2r(\cos \omega_0 T)z^{-1} + r^2 z^{-2}}$$

It is assumed that $r = 1$, that is to say, the poles are on the unit circle, and the angle ω_0 of a pole of the resonator is such that the pole coincides with a zero of the comb filter.

$$\text{Now } \omega_0 = 2\pi k/m \text{ for the function } 1 - z^{-m}$$

$$\omega_0 = 2\pi(k+1/2)/m \text{ for the function } 1 + z^{-m}$$

The poles of the resonator therefore annul the kth zero of the comb filter and its conjugate. Henceforward, we shall call "elementary filter" the resonator used for annulling the kth zero of the comb filter. An elementary filter and a comb filter in cascade form a composite filter having the following properties:

the pulse response has a finite duration mT ,
the amplitude of the response as a function of the frequency is:

$$H(e^{j\omega T}) = \frac{\sin m\omega T/2}{[\cos \omega T - \cos \omega_0 T]}$$

which is zero for any ω which is zero of the comb filter except for ω_0 .

the phase as a function of frequency is quite linear except at the discontinuity points where the phase variations are π radians.

the phase difference between two composite filters of resonance frequency ω_0 and ω_{0+1} is π for $\omega_0 < \omega < \omega_{0+1}$, and zero outside these limits.

the amplitude of any one of the composite filters is zero at the resonance frequencies of all the other composite filters.

The properties show that it is possible to obtain a predetermined amplitude response by adding the weighted outputs of the unit formed of a comb filter and associated elementary filters, in the same way that a limited band function of the time may be formed from weighted sums of the delayed functions $\sin t/t$.

It is this characteristic which is called "frequency sampling."

A frequency response function having a sufficiently narrow band is sampled at regularly spaced points at frequencies in radians.

$$\omega_k = \frac{2\pi k}{m} \text{ or } \omega_k = \frac{2(k+1/2)}{m}, \quad k = 0, 1, \dots, m-1$$

depending on the type of filter used. Let ω_k be the amplitude of the sample at the frequency $\omega_k T$; an elemen-

tary filter of resonance frequency ω_k in series with a comb filter of delay mT and gain $\omega_k \sin \omega_k T$ are used for producing an elementary frequency response of ω_k at the frequency $\omega_k T$ and zero at the other sampling frequencies.

Since the phases at resonance of the consecutive elementary filters differ by π , the gains of the odd-numbered elementary filters have to be multiplied by -1 .

The input signal of the filter is applied to the input of the comb filter which is shared between all the elementary filters, then multiplied by the gains of the filters and by -1 for the odd filters. The outputs of all the elementary filters are added together to give the output signal of the filter in question. This "resultant" filter has a pulse response of duration mT and a frequency response of linear phase; its amplitude response agrees with the specifications at the sampling frequencies and connects the different sampling points without discontinuity. A large variety of filters may be constructed on the basis of this technique.

For practical applications, it is well to take the following considerations into account: The poles of the resonant circuits of the elementary filters cannot quite annul the zeros of the comb filter because of quantization. It is therefore advisable to displace the zeros and the poles slightly to the interior of the unit circle on a radius of the order of $e^{-aT} = 1 - 2^{-28}$. On the circle of radius e^{-aT} , the transfer functions become:

$$\text{for the comb filter } H(z) = 1 - e^{-maT} z^{-m}$$

$$\text{for the elementary filter } H(z) = \frac{1}{1 - 2e^{-aT}(\cos \omega_k T)z^{-1} + e^{-2aT}z^{-2}}$$

FIG. 3 gives a symbolic representation of a type of filter selected for the construction of the frequency receiver according to the invention; in this figure, the squares designated T represent the circuits of sampling period delay, the circles (+) represent the summation circuits and the triangles the multiplication circuits.

These filters are formed of two cells of resonators having slightly offset resonance frequencies. The first cell receives the sample X as an input, that is to say, the coded multifrequency signal; the second cell receives as input the output quantity, divided by g (gain of the first cell), of the first cell.

The difference equations defining these filters for the first cell are

$$Y_{(1)} = X - B_{11} Y_{1(1)} - B_{12} Y_{2(1)}$$

$$S_1 = Y_{(1)} - Y_{2(1)}$$

and for the second cell:

$$Y_{(2)} = S_{1/2} - B_{21} Y_{1(2)} - B_{22} Y_{2(2)}$$

$$S_2 = Y_{(2)} - Y_{2(2)}$$

with

$Y = Y(nT)$ $Y_1 = Y_1(nT - T)$ $Y_2 = Y_2(nT - 2T)$;
the indices (1) and (2) indicate that the expressions relate respectively to cells (1) and (2).

FIG. 4, representing the general circuit diagram of a frequency receiver according to the invention, shows a "filtering" part formed of a computing circuit CC and accessory stores M_1 , M_2 and M_3 and a "treatment" part TR.

The operations to be performed by the computing circuit are:

$$Y = X - B_2 Y_2 - B_1 Y_1$$

$$S = Y - Y_2$$

where:

X is the filter input sample arriving every 125 μ s,
 S is the output sample of the filter, leaving every 125 μ s,

B_1 and B_2 are constant factors,

Y_1 and Y_2 are intermediate results.

The logarithm to base 2 of Y_1 is registered in the store M_1 ; the logarithm to base 2 of Y_2 is registered in the store M_2 ; the logarithms to base 2 of the factors B_1 and B_2 are registered in the store M_3 . At the output SO of the computing circuit CC there appears, offset in time, either the result Y , or the output sample S . The stores M_1 , M_2 , M_3 insert their information into the computing circuit CC respectively by the inputs a , b and c ; the input EX of the input samples X in the computing circuit is operated by d .

FIG. 5 shows in detail in its constituent elements the computing circuit CC which is composed of a block AS_1 for the addition and subtraction of logarithms and a block AS_2 for the addition and subtraction of linear quantities. The inputs of the stores M_1 , M_2 and M_3 are effected on the block AS_1 respectively via a , b and c . The quantities Y_1 , Y_2 , B_1 and B_2 being registered in logarithmic form, the multiplications are replaced by additions of logarithms. On the other hand, normal additions and subtractions are performed on linear quan-

S is then directed to the treatment part TR (FIG. 6).

The operation of the computing device is controlled by a pulse distributor or time base. The treatment of a filter cell is carried out in four elementary times t_1 to t_4 ; 5 during each elementary time, a certain number of operations are performed, several of which commence simultaneously. On the other hand, due to the fact that the frequency receiver operates continuously, it is necessary for the time t_1 to overlap the last time t_4 of the preceding cycle, and for the time t_4 to overlap the first time t_1 of the succeeding cycle.

Thus, at the time t_1 , for the cycle then proceeding, the addition of the logarithms $LB_2 + LY_2$ and the inscription X of the input sample in the register R_2 commence simultaneously, then the logarithms LB_2 and LY_2 are converted into linear quantities and the inscription $B_2 Y_2$ is effected in the register R_1 . For the time t_4 of the preceding cycle which is superimposed on the time t_1 of the cycle then proceeding, the subtraction $S = Y - Y_2$ of linear quantities and conversion from linear to logarithm of the quantity Y commence; then the quantity S is inscribed in the register R_3 and the quantity LY is inscribed in the store of the LY_1 's.

The time t_1 may therefore be summarized (Table I). The arrows f indicate that the operations commence simultaneously:

TABLE I

ties. It is therefore necessary to have a converter C_1 for converting logarithmic quantities into linear quantities, and a converter C_2 for converting linear quantities into logarithmic quantities. The register R_1 registers successively the products $B_2 Y_2$, $B_1 Y_1$ and the quantity Y_2 ; the register R_2 registers successively the quantity X , then $X - B_2 Y_2$, then the quantity Y ; finally, the register R_3 registers the quantity S , output sample. The quantity

55 At the time t_2 , for the cycle in progress, the addition of the logarithms $LB_1 + LY_1$ and the subtraction of the linear quantities $X - B_2 Y_2$ commence simultaneously; then the logarithms $LB_1 + LY_1$ are converted into linear quantities and the quantity $B_1 Y_1$ is inscribed in the register R_1 ; in parallel, the quantity $X - B_2 Y_2$ is inscribed in the register R_2 .

The time t_2 may be summarized thus (Table II):

TABLE II

At the time t_3 , three operations commence simultaneously: (1) the addition of the logarithm LY_2 in the block AS_1 ; (2) the addition and subtraction of the quantities $X - B_2 Y_2 - B_1 Y_1 = Y$ in the block AS_2 ; (3) inscription of LY_1 in the store M_2 . The first operation proceeds by conversion of LY_2 to linear, then by inscription of Y_2 in the register R_1 ; the second operation continues by the inscription of Y in the register R_2 .

The time t_3 may be summarized as follows (Table III):

TABLE III

Superimposed on the time t_4 of the cycle in progress is the time t''_1 of the next cycle; at the start of this time, four operations commence simultaneously, two for the cycle in progress and two for the next cycle. For the cycle in progress, there is the linear addition $S = Y - Y_2$ and the conversion to logarithm of the quantity Y ; then S is inscribed in the register R_3 and the quantity LY is stored in M_1 . For the next cycle, there is the addition of logarithms $LB_2 + LY_2$ and the inscription of X in the register R_2 . Then the conversion to linear of $B_2 Y_2$ is operated and this quantity is inscribed in the register R_1 .

The time t_4 may be summarized as follows (Table IV):

TABLE IV

FIG. 6 shows in detail in its constituent elements the treatment part TR for the output signals of the filters. Detection of the signal by amplitude rectification and its integration by amplitude summation by means of the

detector-adder device DA are performed in the treatment part. Amplitude summation is carried out on eight successive samples and a sample sum store MSE contains the "sum" results of each filter of the receiver.

It is assumed that the diagram of FIG. 6 relates more particularly to the case of a frequency receiver of subscriber signalling of the type $1/P + 1/Q$ (one among $P + 1$ among Q). It is known in fact that the SOCOTEL code is the following:

10 1. Multifrequency code utilizable on an inter-

30 exchange circuit.

There are five code frequencies used for the digits (called code 0-1-2-4-7) to which it is necessary to add a check frequency f_c and a signalling frequency f_{11} .

$$\begin{aligned} F_0 &= 700 \text{ c/s} \\ F_1 &= 900 \text{ c/s} \\ F_2 &= 1100 \text{ c/s} \\ F_4 &= 1300 \text{ c/s} \\ F_7 &= 1500 \text{ c/s} \end{aligned}$$

$$\begin{aligned} F_c &= 1900 \text{ c/s} \\ F_{11} &= 1700 \text{ c/s} \end{aligned}$$

35 40 This code is called "two among five", that is to say that a digit is coded by the superposition of two frequencies.

Thus

$$\begin{array}{ll} 1 - 700 + 900 & 6 - 1100 + 1300 \\ 2 - 700 + 1100 & 7 - 700 + 1500 \\ 3 - 900 + 1100 & 8 - 900 + 1500 \\ 4 - 700 + 1300 & 9 - 1100 + 1500 \\ 5 - 900 + 1300 & 0 - 1300 + 1500 \end{array}$$

2. Keyboard code utilizable between the subscriber and his connected exchange; this is a code $1/P + 1/Q$ with $P=3$ and $Q=4$

$$\begin{aligned} P_1 &= 1500 \text{ c/s} \\ P_2 &= 1650 \text{ c/s} \\ P_3 &= 1800 \text{ c/s} \end{aligned}$$

$$\begin{aligned} Q_1 &= 2200 \text{ c/s} \\ Q_2 &= 2350 \text{ c/s} \\ Q_3 &= 2500 \text{ c/s} \\ Q_4 &= 2650 \text{ c/s} \end{aligned}$$

A digit is coded by the superposition of two frequencies, one of which belongs to the group P and the other to the group Q.

Thus

$$\begin{array}{llllll} 1 - P_1 + Q_1 & 4 \rightarrow P_1 + Q_2 & 7 \rightarrow P_1 + Q_3 & 10 \rightarrow P_1 + Q_4 \\ 2 - P_2 + Q_1 & 5 \rightarrow P_2 + Q_2 & 8 \rightarrow P_2 + Q_3 & 11 \rightarrow P_2 + Q_4 \\ 3 - P_3 + Q_1 & 6 \rightarrow P_3 + Q_2 & 9 \rightarrow P_3 + Q_3 & 12 \rightarrow P_3 + Q_4 \end{array}$$

The store MSE (FIG. 6) is a circulation (series-parallel) store comprising one word of 12 bits per filter of the frequency receiver, that is to say seven words for a receiver of seven filters for the case considered. This shift store advances in synchronism with the computing instants relative to each of the filters. During the treatment of a filter, the word of the store MSE appears at the output of the store and therefore at one of the inputs of the adder DA by the wire SM; at the end of the calculations relating to the filter, the output sample of the filter is inscribed in the register R_3 (see FIG. 5), whose output S is connected to the second input of the adder DA. The latter has its outputs connected to the shift store MSE. Every eight sampling periods, that is to say after having summed the amplitudes of 8 samples, analysis of the energies in each filter of the receiver is made.

The filter energy analysis circuits consist of four shift registers RAEF receiving on command, in parallel and at the same instant, the contents of the first four words starting from the output of the store MSE. After the posting of these registers, they are shifted, heavily weighted at the front (in the direction of the arrows), and the outputs of these four registers enter the maximum value test circuit TVM.

To define the filter having maximum energy, it is sufficient to test which of the four shift registers first presents a "1" at its output (since these registers are shifted heavily weighted at the front). This single test, however, is not sufficient; in fact, when a pure frequency is present in a filter of the receiver, the ratio between the energy in this filter and the energy in the adjacent filters is at least 10 decibels. Therefore, we decide that one frequency is present in a filter (out of four or three, depending on whether it is a matter of group Q or group P) only if the ratio between the filter which has the heaviest weight and the energy in each of the other filters is at least 8.

The maximum value test circuit TVM has four outputs, only one of which is active if the test is valid and indicates the number of the filter of the group P (three frequencies) or group Q (four frequencies) which has the maximum value, that is to say, indicates the frequency present in the group.

After having determined successively the frequency present in the group P, then in the group Q, the code $1/P + 1/Q$ is binary coded at four bits and transmitted to the output of the frequency receiver.

So that the result at the output of the frequency receiver will not be zero, it is necessary that there should be one frequency and only one present in each

of the groups P and Q; it is then said that the result is coherent.

FIG. 7 gives a comparison of the output signals of two filters receiving the same input signal.

5 It is assumed that the input signal X in the frequency receiver is formed of the sum of two sinusoidal signals of respective frequencies $f_1 = 900 \text{ c/s}$ and $f_2 = 1300 \text{ c/s}$, but having the same amplitude. Also assumed are two adjacent filters F_1 and F_2 such that the filter F_1 is formed of a cell centered on $1,300 \text{ c/s}$ and filter F_2 is formed of a cell centered on $1,100 \text{ c/s}$.

10 FIG. 7 shows three graphs 7-I, 7-II and 7-III of amplitude as a function of the time for sampling instants spaced by the duration T of a sampling period.

15 The graph 7-I gives the amplitude of the input signal X formed of $f_1 + f_2$ at 10 successive instants spaced by T.

20 The graph 7-II gives the amplitude of the output signals S of the filter F_1 centered on $1,300 \text{ c/s}$, and which therefore receives at the maximum the signals f_2 of $1,300 \text{ c/s}$.

25 The graph 7-III gives the amplitude of the output signals of the filter F_2 centered on $1,100 \text{ c/s}$, and which therefore receives neither the frequencies f_1 centered on 900 c/s nor the frequencies f_2 centered on $1,300 \text{ c/s}$. It will be observed that despite an amplitude scale of the output signals of F_2 10 times greater than that of F_1 or of $f_1 + f_2$, the output signals of F_2 are very weak. The 30 output energies of these two adjacent filters are in a ratio of about 30 decibels and, consequently, the signal detected and to be retained is the signal f_2 alone, collected at the output of F_1 .

35 An actual operational example of filtering by the computing device, FIGS. 4 and 5, will now be given with reference to FIGS. 8 and 9. The operation of a filter all in four elementary times t_1 to t_4 has already been described; actually a filter is composed of two cells having slightly offset resonance frequencies and is

40 treated in six elementary times since we have seen that, during the fourth time of the treatment of a cell, the operations of the first time of the next cell are also treated. In the treatment of a two-cell filter, therefore, the first time is utilized for treating the last operations

45 of the second cell of the preceding cycle, the second and third times are utilized for treating solely the first cell of the cycle in progress, the fourth time terminates the treatment of the first cell and commences the operations of the second cell, the fifth and sixth cells

50 are utilized solely for the second cell of the cycle in progress, and the end of the treatment of this second cell will be effected in the first treatment time of the first cell of the next cycle; there is therefore overlapping in the first time t_1 and in the fourth time t_4 ; in the first time, overlapping occurs over two adjacent cycles, in the 4th time overlapping occurs on the two cells of the same cycle. This is shown in FIGS. 8 and 9, where C_1E_1 represents the first treatment cell of the

55 first sample, C_2E_1 represents the second treatment cell of the first sample, C_1E_2 represents the first treatment cell of the second sample, C_2E_2 represents the second treatment cell of the second sample, etc.; the treatment of C_1E_1 occurs in the times t_1 to t_4 , the treatment of C_2E_1 occurs in the times t_4 to t_6 of the 1st cycle and in the time t_1 of the 2nd cycle (FIG. 9); likewise, the treatment of C_1E_2 occurs in the times t_1 to t_4 of the second cycle and the treatment of C_2E_2 occurs in the times t_4 to t_6 of the second cycle and in the time t_1 (not shown) of

the third cycle, etc., a complete cycle corresponding to the treatment of one sample. By way of example, the numerical operation of a two-cell filter will now be described; to facilitate the computations, two identical cells, that is to say having the same resonance frequency, will be assumed; the coefficient of the difference equations have the value:

$$B_{11} = B_{21} = 1.414 = B_1$$

$$B_{12} = B_{22} = 0.973 = B_2$$

We thus the following difference equations:

$$Y_{(1)} = X - 1.414 Y_{1(1)} - 0.973 Y_{2(1)}$$

$$S_{(1)} = Y_{(1)} - Y_{2(1)}$$

$$Y_{(2)} = S_{1/32} - 1.414 Y_{1(2)} - 0.973 Y_{2(2)}$$

$$S_2 = Y_{(2)} - Y_{2(2)}$$

The bracketed subscripts refer to the cells 1 or 2 of the filter. To facilitate matters, input samples, which are constant in time, are assumed, for example

$$X = +176 \text{ (} X \text{ capable of varying from 0 to 1,000).}$$

In binary form $|X| = 0010110000$ with Sg (sign) $X = 1$, the sign of X being assumed equal to 1 if X is positive and equal to 0 if X is negative.

The coefficients are expressed as logarithms to the base 2.

$$(1) \quad -B_1 = -414$$

The logarithm of B_1 expressed in binary form is $|LB_1| = 0000, 100000$ with $Sg LB_1 = 1$ and $Sg B_1 = 0$ (B_1 being greater than 1 has a positive logarithm).

$$(2) \quad -B_2 = -0.973$$

The logarithm of B_2 expressed in binary form is $|LB_2| = 0000, 000101$ with $Sg LB_2 = 0$ and $Sg B_2 = 0$ (B_2 being less than 1 has a negative logarithm).

$$(3) \quad -1$$

The logarithm of 1 is $L_1 = 0000, 000000$ with $Sg L_1 = 1$ and $Sg (-1) = 0$.

FIGS. 8 and 9 give in tabular form the binary values of LB_1 and LB_2 registered in the store M_3 , LY_1 registered in M_1 and LY_2 registered in M_2 , as well as the value of their sign; there is also shown the contents of each of the registers R_1 , R_2 and R_3 of FIG. 5 in the course of the six elementary treatment times of the filter for two successive samples of the input signal, FIG. 8 giving the treatment of the first input sample and FIG. 9 the treatment of the second input sample. For each elementary time $t_1, t_2 \dots$ therefore, the modified or non-modified state of the stores M_1, M_2 and M_3 , as well as that of the registers R_1 to R_3 are again shown; R_3 , however, since it intervenes only at the time t_1 , is indicated only for this time alone.

At the commencement of the operations, the registers R_1, R_2 and R_3 are at zero, as are also the stores M_1 for LY_1 , M_2 for LY_2 . We then consider FIG. 8 after the arrival of the 1st sample: in the t_1 the following are performed: inscription of the sample X in the register R_2 , that is to say, as we have just seen, of the binary quantity 0010110000 with its sign 1 and the inscription of the result (which is zero) $-B_2 Y_{2(1)}$ in the register R_1

with its sign 1; with $LB_2 = 0000000101$ (see Table I of the text);

in the time t_2 the following are performed: addition (or subtraction) of the contents of the registers R_1 and R_2

5 with inscription of the result in the register R_2 at the end of the time t_2 ; this is the operation $X - B_2 Y_{2(1)}$, the result (0010110000) of which remains the same as in the time t_1 since $B_2 Y_2 = 0$; there is also inscribed in the register R_1 the result of the product (zero) $-B_1 Y_{1(1)}$;

10 with $LB_1 = 0000100000$ (see Table II of the text); in the time t_3 , the following are performed: addition or subtraction of the contents of registers R_1 and R_2 with inscription register 2 at the end of the time t_3 , that is to say, the operation $X - B_2 Y_{2(1)} - B_1 Y_{1(1)} = Y_{(1)}$, translated

15 by 0010110000 with the sign 1; inscription of the word of store LY_1 in store M_2 at the end of the time t_3 ; the operation $-1 \times Y_{2(1)}$ with inscription of the result in register R_1 , at the end of the time t_3 (see Table III of the text).

20 in the time t_4 the following are performed: inscription, at the end of time t_4 , in store M_1 , of the logarithm of in contents of register R_2 ; the contents of register R_2 in binary form is the number 0010110000 which, in logarithmic form, is 0111, 011000; inscription in the register R_2 , at the end of the time t_4 , of the contents of register R_2 divided by $2^5 = 32$ gain of the first cell, that is to say in fact, inscription in register R_2 of the contents of the register shifted to the right (low weight side) by

30 five elements, that is to say by $S_1/32$ or 0000000101; inscription in register R_1 of the product $-B_2 Y_{2(2)}$ which is zero with its sign 1;

in the time t_5 the following are performed: addition (or subtraction) of the contents of registers R_1 and R_2 with

35 inscription in register R_2 at the end of the time t_5 ; this is the operation $S_1/32 - B_2 Y_{2(2)}$ translated by the binary number 0000000101 with the sign 1, since $-B_2 Y_{2(2)}$ is zero; finally, inscription in register R_1 of the product $-B_1 Y_{1(2)}$ which is zero with the sign 1;

40 in the time t_6 the following are performed: addition (or subtraction) of the contents of registers R_1 and R_2 with inscription in register R_2 at the end of the time t_6 ; this is the operation $S_1/32 - B_2 Y_{2(2)} - B_1 Y_{1(2)} = Y_2$, which is again translated by the same binary number

45 0000000101, since $-B_2 Y_{2(2)}$ and $-B_1 Y_{1(2)}$ are zero; then the operation $-1 \times Y_{2(2)}$ with inscription in the register R_1 at the end of the time t_6 ; finally, inscription of LY_1 in store M_2 ; the following time t_1 , therefore, concerns simultaneously the end of the treatment of the sample

50 in progress $C_2 E_1$ and the commencement of the treatment of the next sample $C_1 E_2$ (FIG. 9). Register R_1 indicates the magnitude of the output S after the treatment of the 1st sample which is the transfer of register R_2 of the time t_6 , that is to say 0000000101; register R_1 receives $B_2 Y_2$ which is zero; register R_2 receives the new input sample, assumed to be the same as in the preceding cycle, that is to say 0010110000 with the sign 1;

55 60 in the store M_3 there is again, as at the time t_1 of the 1st cycle, the quantity LB_2 expressed by the binary number 0000000101; the store M_1 contains the logarithm of the input sample in binary code, that is to say, 0111011000, left since the time t_4 of the preceding cycle;

65 in the time t_2 of the 2nd cycle, the following are performed: addition (or subtraction) of the contents of registers R_1 and R_2 , that is to say, the operation $X - B_2 Y_2$

which is inscribed in register R_2 at the end of the time t_2 under the binary number 0010110000, which in fact amounts to transferring R_2 since R_1 is zero; in register R_1 there is also inscribed the result of the product $-B_1Y_1$, that is to say, the sum of the stores M_3 and M_1 , i.e., the binary number 0011110000 with $LB_1 = 000010000$ and $LY = 0111011000$; in the time t_3 of the 2nd cycle the following are performed: addition (or subtraction) of the contents of the registers R_1 R_2 with inscription in register R_2 at the end of the time t_3 , that is to say, the operation $X - B_2Y_2 - B_1Y_1$, translated by the binary number 0001000000; inscription of the word of store LY_1 in store M_2 at the end of the time t_3 ; the operation $-1 \times Y_2$ with inscription of the result in register R_1 at the end of the time t_3 ;

in the time t_4 of the 2nd cycle, the following are performed: inscription at the end of time t_4 , in the store M_1 , of the quantity LY which in binary form is the number 0111011000; inscription in register R_2 at the end of the time t_4 of the contents of register R_2 divided by $2^5 = 32$, gain of the preceding cell, that is to say in fact, inscription in register R_2 of the contents of the register shifted to the right (low weight side) by five elements, that is to say, $S_1/32$ or 000000010; inscription in register R of the product $-B_2Y_2$, which is zero with its sign 1;

in the time t_5 of the 2nd cycle the following are performed: addition (or subtraction) of the contents of registers R_1 and R_2 with inscription in register R_2 at the end of the time t_5 , which amounts practically to preserving the contents of the register R_2 since the content of R_1 is zero; finally, inscription in register R_1 of the product $-B_1Y_1$, that is to say, of the sum of the stores M_3 and M_1 , or the binary number 0000000111 after log-linear conversion;

in the time t_6 of the 2nd cycle, the following are performed: addition (or subtraction) of the contents of registers R_1 and R_2 with inscription in register R_2 at the end of the time t_6 of the binary number 0000001001; then the operation $-1 \times Y_2$ with inscription in register R_1 , or here zero result with the sign 1.

Of course, the invention is by no means limited to the embodiment described and shown, which has been given only as an example; more particularly it will be possible to modify certain arrangements or replace certain means by equivalent means without departing from the scope of the invention.

We claim:

1. A numerical frequency analyzing apparatus for use in a telecommunication system comprising:

means for receiving binary coded samples of voice frequency signals; and

means for detecting component frequencies among each of a plurality of said frequency signals, the frequencies being detected from a predetermined number of frequencies including:

a plurality of band-pass digital filters corresponding to said predetermined number of frequencies in the signals capable of being received, coupled to the output of said receiving means,

means responsive to the outputs of said digital filters for determining the amount of energy in the outputs thereof, and

means, responsive to said energy determining means, for selecting filters corresponding to component frequencies of each signal, the energies of which exceed a predetermined threshold level.

2. An apparatus according to claim 1, wherein said plurality of band-pass filters are formed from a combination of a computing circuit and a plurality of accessory store elements connected thereto, wherein said computing circuit receives an input signal sample X at a prescribed sampling frequency, and provides a first intermediate resultant quantity $Y = X - B_2Y_2 - B_1Y_1$, where B_1 and B_2 represent first and second characteristic constant coefficients of a filter and Y_1 and Y_2 represent said quantity Y which has been delayed through first and second sampling delay periods, and an output quantity $S = Y - Y_2$ wherein the quantities B_1, B_2, Y_1, Y_2 are registered in said accessory store elements and wherein said energy determining means includes means for summing the sample outputs of said computing circuit.

3. An apparatus according to claim 2, wherein said computing circuit comprises:

a first computing block means, responsive to the contents of said accessory store elements for combining said contents in the form of logarithmic quantities;

a first converter means, responsive to the outputs of said first computing block means, for converting said logarithmic quantities into first linear quantities;

a first register, responsive to the output of said first converter means for storing said first linear quantities;

a second computing block means, responsive to the output of said first register, for combining said first linear quantities;

a second register, responsive to the output of said second computing block means, for storing the output of said second computing block means in linear form;

a third register, responsive to the output of said second computing block means and linear quantities representative of said input sample, for storing the inputs thereto, the outputs of said third register being connected to one input of said second computing block means; and

a second converting means responsive to the outputs of said third register, for converting the contents thereof into logarithmic form and feeding said logarithmic quantities to one of said accessory store elements;

and further including means for supplying timing signals to each element within said computing circuit for controlling the sequential operation thereof.

4. An apparatus according to claim 3, wherein said energy determining means comprises:

said summing means including a detector-adder circuit, responsive to the output of said second register, for rectifying the amplitudes of the sample outputs thereof and summing said rectified amplitudes of a prescribed number of successive signal samples;

a calculation store element, responsive to the summed sample outputs of said detector-adder circuit, for storing successive sum quantities of samples corresponding to the respective digital filters; means, responsive to the stored sums in said calculation store element, for shifting and weighting said quantities and providing said shifted and weighted quantities at a plurality of respective outputs; and

wherein said selecting means includes a maximum value testing circuit for determining, from among the outputs of said shifting means, the quantity having the maximum amount of energy.

5. An apparatus according to claim 4, wherein said plurality of accessory storage elements comprises first, second and third accessory store elements, said first accessory store element storing the logarithmic of said quantities Y and Y_1 , the output of said first accessory store being connected to said computing circuit and to the input of said second accessory store circuit for storing the logarithm of the quantity Y_2 , and wherein said third accessory store stores the logarithms of said characteristic filter constant coefficients B_1 and B_2 , the 10 outputs of said second and third accessory store elements being connected to said computing circuit.

6. An apparatus in accordance with claim 4, wherein said detector adder circuit includes a first input connected to the output of said second register and a 20 second input connected to the output of said calculation store element.

7. An apparatus in accordance with claim 6, wherein said selecting means includes means, responsive to the contents of said shifting means, for testing the ratio of 25 the respective outputs thereof and for indicating the presence of a selected frequency only when said ratio exceeds a predetermined value.

8. A method of analyzing samples of voice frequency signals comprising the steps of : 30

a. simultaneously adding, in a first computing block means, the logarithms of a first quantity B_2 of a band-pass digital filter provided in a plurality of band-pass digital filters corresponding to the 35 respective different component frequencies in which useful information is contained and to which information signals are applied, a quantity Y_2 corresponding to a quantity $Y = X - B_2 Y_2 - B_1 Y_1$, which has been delayed through first and 40 second sampling delay periods, where B_1 and B_2 represent first and second characteristic constant coefficients of a filter, and Y_1 and Y_2 represent said quantity Y which has been delayed through first and second sampling delay periods, respectively, 45 the logarithms of said quantities Y_1 , Y_2 , B_1 and B_2 being stored in a plurality of accessory store elements, said first computing block means being responsive to the contents thereof in the form of logarithmic quantities, and 50 storing an input sample X in a first register and, subsequently,

converting in a first converter means, responsive to the output of said first computing block means, for converting the logarithmic quantity 55 of said first computing block means into first

linear quantities, the logarithmic sum of said output B_2 and Y_2 into a linear quantity $B_2 Y_2$ and storing said quantity $B_2 Y_2$ in a second register which is responsive to the output of said first converter means, during a first period of time;

b. adding, in said first computing block means, the logarithm of the quantities B_1 and Y_1 and subtracting, in a second computing block means, which is responsive to the output of said second register, for combining said first linear quantities, the quantity $B_2 Y_2$ from the input signal sample X , simultaneously, and subsequently, converting the sum of the logarithms B_1 and Y_1 into a linear quantity $B_1 Y_1$, in said first converter means, and storing said quantity $B_1 Y_1$ in said second register, and storing the difference quantity $X - B_2 Y_2$ in said first register, during a second period of time;

c. combining the linear quantities $X - B_2 Y_2$, and $B_1 Y_1$ in accordance with the equation $Y = X - B_2 Y_2 - B_1 Y_1$ in said second computing block means, storing the logarithm of the quantity Y_1 in one of said plurality of accessory store elements and applying the logarithm of the quantity Y_2 to said first computing block means, simultaneously, and

converting the logarithm of the quantity Y_2 into a linear quantity in said first converter means and storing said linear quantity Y_2 in said second register and, further

storing in said first register said quantity Y , resulting from the combination of the linear quantities X , $B_2 Y_2$ and $B_1 Y_1$ in said second computing block means, during a third period of time;

d. subtracting, in said second computing block means, the output quantity Y_2 from the quantity Y , to product a difference quantity S and converting the quantity Y into logarithmic form in a second converter means which is responsive to the output of said first register, for converting the contents thereof into logarithmic form and feeding said logarithmic quantities to a second of said accessory store elements, and

subsequently storing said quantity S in a third register, which is responsive to the output of said second computing block means, for storing the output of said second computing block means in linear form, and the logarithm of the quantity Y in said second of said accessory store elements, respectively during a fourth period of time; and repeating step (a) coincident with the execution of step (d).
